UNITED STATES PATENT OFFICE

TULLY LA TESSA, OF CHICAGO, ILLINOIS, ASSIGNOR TO THE MERIT COMPANY, OF CHICAGO, ILLINOIS, A CORPORATION OF ILLINOIS

DESIGN FOR A CASKET

Application filed May 4, 1929. Serial No. 31,102. Term of patent 14 years.

To all whom it may concern:

Be it known that I, TULLY LA TESSA, a citizen of the United States, residing in Chicago, county of Cook, and State of Illinois, have invented a new, original, and ornamental Design for a Casket, of which the following is a specification, reference being had to the accompanying drawings, forming part thereof.

In the drawings—

vation of the casket, showing my new design.

Figure 2 is a view representing, on a smaller scale, a side elevation of said casket, part of the same being indicated in dotted lines, it being understood that the ornamentation is continued throughout.

I claim:—

The ornamental design for a casket as shown and described.

TULLY LA TESSA.
